UNITED STATES PATENT OFFICE.

ALFRED COTTON, OF ST. LOUIS, MISSOURI, ASSIGNOR TO HEINE BOILER COMPANY, OF ST. LOUIS, MISSOURI, A CORPORATION OF MISSOURI.

WATER-TUBE BOILER.

Application filed March 20, 1922. Serial No. 545,134.

To all whom it may concern:

- Be it known that I, ALFRED COTTON, a citizen of the United States, residing at St. Louis, Missouri, have invented a certain 5 new and useful Improvement in Water-Tube Boilers, of which the following is a full, clear, and exact description, such as will enable others skilled in the art to which it appertains to make and use the same.
- 10 This invention relates to water tube boilers of the type in which the water tubes are arranged in a horizontally-inclined position between front and rear header structures to which the ends of said tubes are connected.
- 15 The water tube boilers of this general type that are now in use comprise a main tube bank of relatively long tubes that is divided into a plurality of gas passes either by transversely-disposed baffles arranged in 20 such a way as to cause the gases to flow transversely across the tubes, or longitudinally-disposed baffles arranged in such a way as to cause the gases to flow lengthwise of the tubes. The baffles of water tube boilers of 25 the general type referred to are difficult and expensive to construct and in most instances it is virtually impossible to inspect them. They become defective and leaky in service, but there is no way of ascertaining this except by suspicion engendered by reduced 30 boiler efficiency. Owing to the fact that such baffles are so inaccessible that they can only be repaired when the boiler is not in operation, the waste, due to defective baffles, is 35 frequently allowed to continue for long periods, as it is often almost impossible, or at least highly undesirable, to shut the boiler down long enough to enable the baffles to be repaired. Cross baffles are particularly 40 expensive to construct, and due to the fact that they are arranged transversely of the tubes, they are very liable to become damaged when renewing the water tubes of the boiler.
- 45 The main object of my invention is to provide a water tube boiler of the type that comprises horizontally-inclined tubes which is of such construction that a long, tortuous gas passageway of diminishing cross-sectional area is obtained without baffles or without inaccessible baffles that cannot be 50 inspected or repaired easily, thereby produc-

ing a highly efficient boiler that is free from the troubles common to the boilers of this general type which are now in commercial 55 use.

Another object is to provide a water tube boiler of the general type referred to in which all of the heating surface is fully utilized; in which the resistance to flow of the 60 gases is reduced to the minimum and which is compact, easily accessible and inexpensive to construct. Other objects and desirable features of my invention will be hereinafter 65 pointed out.

Briefly stated, my invention consists of a water tube boiler provided with a main tube bank of uniform width throughout its entire height but of diminishing cross-sectional area, through which the gases make a single 70 pass, composed of horizontal or horizontally-inclined water tubes of gradually diminishing length, a header structure arranged at one end of the tubes constituting said bank and an inclined header structure arranged 75 at the opposite ends of said tubes and set at such an angle with relation to the header structure first referred to as to form a gas passageway of uniform width throughout its entire length or height, but of gradually 80 diminishing depth from its lower towards its upper end.

Figure 1 of the drawings is a vertical longitudinal sectional view of a water tube boiler constructed in accordance with my 85 invention.

Figure 1^a is a longitudinal sectional view, 90 illustrating a portion of a boiler of the construction shown in Figure 1 equipped with a superheater.

Figures 2 and 3 are vertical longitudinal sectional views, illustrating other forms of my invention; and

Figure 3^a is a view, illustrating another 95 form of inclined front header.

Referring to Figure 1 of the drawings, which illustrates the basic idea which my improved boiler embodies, A designates the combustion chamber of the boiler and B designates the main tube bank which is 100 composed of horizontally-inclined water tubes 1, a rear header structure composed preferably of vertically-disposed, sectional headers 2 to which the rear ends of the

tubes 1 are connected and a front header structure composed preferably of inclined sectional headers 3 of stepped form or zig-zag shape to which the front ends of the tubes 1 are connected. Above the main tube bank B is a shallow top bank C composed of relatively long water tubes 4 arranged parallel to the tubes of the main bank B and connected at their front and rear ends to headers 5 and 6 which are connected with the front and rear header structures of the main bank B by means of water circulators 7 and 8, respectively. A transverse steam-and-water drum D is connected by means of water circulators 9 with the front header structure 5 of the top bank C, and said drum is connected by means of steam circulators 10 with the rear header structure 6 of the top bank C. The substantially triangular-shaped space between the front wall of the setting of the boiler and the inclined front header structure 3 of the main bank C constitutes a dust and ash collection chamber E that is large enough to allow a large accumulation of dust and fly ash and to which access may be had through a door opening 11 in one of the side walls of the boiler setting. If desired, the front wall of the setting may be provided with a door or doors 12 so as to permit the dust and ash to be removed from the chamber E by devices inserted between the water circulators 7 that connect the front header structures of the two tube banks of the boiler. Preferably, plates 13 provided with handles 13^a are mounted on the inclined front headers 3 of the main tube bank B so as to prevent dust and ash from collecting on the hand hole plates (not shown) of said front headers, the plates 13 being narrow enough to permit them to be removed easily from the dust collection chamber E. A shield 14 that is arranged on the upper side of the top bank C extends forwardly from the rear header structure 6 of said bank to an uptake 15 that leads to a chimney or stack 16 and the steam circulators 10 that connect the steam-and-water drum D with the rear header structure 6 of the top bank C are protected by the top wall 17 of the boiler setting.

When the boiler is in operation the gases rising from the fire flow upwardly across the tubes of the main bank B and then longitudinally of the shallow top bank C to the uptake 15 at the front end of said top bank. Owing to the fact that the boiler comprises a shallow top bank C of long tubes that is arranged above the main tube bank B, the heating surface of the boiler is equal to the heating surface of a conventional, horizontally-inclined tube boiler having a single tube bank of long tubes that is divided into a number of passes by transversely-disposed cross baffles. As the gases

do not make sharp reversal turns, the resistance to the flow of the gases in my boiler will be smaller than in a conventional, horizontally-inclined tube boiler, which means that the draft loss through the boiler will be smaller than is the case with a boiler having a single tube bank equipped with baffles that cause gases to flow in opposite directions in traveling through the bank. 70

If desired, a superheater F can be arranged in the space between the main tube bank B and the top bank C, as shown in Figure 1^a. 75

In Figure 2 of the drawings I have shown another form of my invention consisting of a boiler having the desirable features and characteristics of the boiler shown in Figure 1 and equipped with a bank G of long tubes exposed to the radiant heat of the combustion chamber A. Most of the elements of the boiler shown in Figure 2 are of the same construction and arrangement as the elements of the boiler shown in Figure 1, and accordingly, have been designated by corresponding reference characters. The main difference consists in the addition of the radiant heat bank G of long water tubes arranged between the combustion chamber A and the main tube bank B and the addition of a superheater H that is arranged directly above the radiant heat bank G in the space between said bank and the main tube bank B. By arranging the superheater in this position it will be exposed to higher temperature gases than the superheater shown in Figure 1^a. Consequently, it may be made smaller because the heating surface is more effective. In the boiler shown in Figure 2 the inclined front headers 3 of the main bank are provided at their lower ends with forwardly-projecting extensions 3^a that overhang the front end portions of the tubes of the radiant heat bank G, and the spaces between said extensions are packed with refractory material so as to form a wall that prevents the gases from short-circuiting into the dust collection chamber E. It is preferable but not absolutely necessary to arrange a shield at the upper side of the front end portion of the radiant heat bank G, so as to protect the lower end portions of the inclined front headers 3 from the hot gases, the shield of the boiler herein illustrated being formed by tiles 18 arranged over the front end portions of the topmost tubes of the radiant heat bank and a transversely-disposed member 18^a at the front end of the superheater chamber which projects upwardly high enough to protect the forwardly projecting extensions 3^a at the lower ends of the inclined front headers 3 of the main tube bank. Another slight difference between the boiler shown in Figure 2 and the boiler shown in Figure 1 is that the shield 14^a 105

110

115

120

125

130

arranged above the top bank C is so constructed that the flow of the gases through said top bank is partly longitudinally of said bank and partly transversely of said bank. Fewer tubes are used in the top bank of the boiler shown in Figure 2, but there is no serious throttling of the gases in traveling through said top bank, owing to the fact that openings 19 and 20 are provided 5 at opposite ends of the shield 14^a, so as to permit a shunt flow of some of the gases into a dust collection chamber I above the top bank, as indicated by the arrows in Figure 2. When the boiler shown in Figure 2 is in operation part of the gases that escape from the upper end of the main bank B flow longitudinally of the top bank C into the uptake 15 and the remainder of said gases flow transversely across the rear 10 end portion of the tubes of the top bank C into the chamber I and then downwardly through the opening 20 among the tubes of the top bank C, finally escaping upwardly through the uptake 15. Accordingly, in the boiler shown in Figure 2 the flow of the gases relative to the top bank C is partly longitudinally of said bank and partly transversely of said bank, and gas pockets are avoided, while the resistance to 15 gas flow is small with low draft loss. The avoidance of gas pockets increases the effective heating surface of the boiler and increases its efficiency over the conventional, horizontally-inclined tube boilers of the kind 20 now in commercial use. Any deposit of dust on the shield 14^a of the boiler shown in Figure 2 is not objectionable, since such dust does not lie on the heating surface of the boiler. Even if the removal of such 25 dust is neglected, it will eventually be carried down into the dust collection chamber E through the opening 20 at the lower end or front end of the downwardly-inclined shield 14^a arranged above the top bank.

While I prefer to construct the top tube bank of my improved boiler in the manner illustrated in Figure 2, it is not essential that the top tube bank be constructed in the manner illustrated in Figure 2 or in Figure 1, 30 for if desired, the boiler may be provided with a rather high top tube bank C', as shown in Figure 3, equipped with cross baffles 21 and 22 arranged in such a way as to cause the gases to make a number of transverse passes in traveling from the main tube bank B to the uptake 15. Due to the fact that the top bank C' of the boiler illustrated in Figure 3 is shallow, as compared to the main tube bank B, being a maximum of about eight tubes high or deep, the cross baffles 21 and 22 of said top bank are accessible either from above or below said bank. Consequently, the baffles of the top bank C' can be readily inspected and they 35 can be easily installed or repaired, as no por-

tion of either baffle of the top bank is spaced more than four tubes from the outside of the bank.

The gases flowing through a boiler drop rapidly in temperature after entering the 70 gas passage and drop slowly at the end of said passage. As the volume is directly proportional to the absolute temperature, it is desirable to make the gas passage of such form that the velocity of the gases traveling 75 through same will be kept constant. In a boiler of the construction illustrated in Figures 1, 2 and 3, the gases flowing through the main tube bank will be maintained at a substantially constant velocity, due to the 80 fact that the gas passage in the main tube bank is formed by the two side walls of the boiler setting, the rear headers 2 and the front headers 3 which are set at such an angle with relation to the rear headers as to 85 form a gas passage of diminishing area from its lower towards its upper end. If, however, it is desired to hold the velocity of the gases within closer limits, the main tube bank can be provided with front headers 90 that are curved slightly, as shown in Figure 3^a, wherein the dot and dash line x—x representing the longitudinal axis of the front headers, approximates a volume curve of the 95 gases flowing through the main tube bank.

In addition to the advantages and desirable features above pointed out, my improved boiler is of exceedingly simple design and is of such construction that it can be equipped either with transverse, vertical or horizontally-disposed soot blowers. With such a boiler it is not necessary to carry a large stock of tubes for renewals, for the tubes which fail most frequently are those nearest the fire, and these tubes are long 100 tubes. If long tubes only are carried in stock, they can be cut down for the renewal of short tubes, and as short tubes fail very seldom, the loss due to cutting is outweighed 105 by the less amount of stock it is necessary to carry on hand.

Having thus described my invention, what I claim and desire to secure by Letters Patent is:

1. A water tube boiler provided with a main tube bank composed of tubes that diminish in length in the direction in which the gases flow through the boiler, an inclined header structure arranged between the said bank and one wall of the boiler setting so as to form a dust collection chamber between said wall and header structure, and a top tube bank arranged so that a portion of same extends beyond said header structure and over said dust collection chamber.

2. A water tube boiler having a main tube bank provided at one end with an inclined header structure that is spaced away from one wall of the boiler setting so as to form a dust collection chamber between said wall

and header structure, and a top tube bank arranged so that one portion of same is positioned over said main tube bank and a different portion of same is positioned over said dust collection chamber.

3. A water tube boiler provided with a main tube bank composed of horizontally-inclined tubes which decrease gradually in length from the lower towards the upper end of said bank, a rear header structure to which said tubes are connected at their rear ends, a front header structure connected to the front ends of said tubes and spaced away from the front wall of the boiler setting so as to form a dust collection chamber between said front wall and said front header structure, and a top bank of relatively long tubes arranged so that a portion of same extends forwardly over said chamber.

20. 4. A water tube boiler provided with a main bank of horizontally-inclined water tubes arranged so that the gases from the fire will flow transversely across same, angularly-disposed header structures combined with said tubes in such a way as to form a gas passageway of gradually diminishing area from its lower towards its upper end, a top tube bank composed of relatively long water tubes combined with header structures that are connected by circulators with the header structures of the main bank, and a steam-and-water drum connected by water circulators and steam circulators with the header structures of said top bank.

35. 5. A water tube boiler having a main tube bank, comprising horizontally-inclined water tubes arranged above the combustion chamber, an inclined header structure at one end of said bank spaced away from a wall of the boiler setting so as to form a dust collection chamber between said wall and header structure, a gas uptake at the upper end of the boiler arranged above said dust collection chamber, and a top tube bank arranged between said gas uptake and said main tube bank and provided with a portion that overhangs said dust collection chamber.

60. 6. A water tube boiler having a main tube bank, comprising horizontally-inclined water tubes arranged above the combustion chamber, an inclined header structure at one end of said bank spaced away from a wall of the boiler setting so as to form a dust collection chamber between said wall and header structure, a gas uptake at the upper end of the boiler arranged above said dust collection chamber, a top tube bank arranged between said gas uptake and said main tube bank and provided with a portion that extends over said dust collection chamber, means for facilitating the removal of dust from said chamber, and means for preventing dust from accumulating on the inclined header structure of said main bank.

7. A water tube boiler, comprising a main bank composed of horizontally-inclined water tubes and angularly-disposed header structures combined with said tubes, a top bank composed of relatively long water tubes arranged above said main bank, a radiant heat bank arranged between said main bank and the combustion chamber of the boiler, and means for causing the gases to flow partly longitudinally of and partly transversely of said top bank.

8. A water tube boiler, comprising a main bank composed of horizontally-inclined water tubes and angularly-disposed header structures combined with said tubes, a top bank composed of relatively long water tubes arranged above said main bank, a radiant heat bank arranged between said main bank and the combustion chamber of the boiler, an uptake leading from one end of said top bank, and means combined with said top bank for causing part of the gases that escape from the main bank to flow longitudinally of the top bank and the remainder of said gases to make a plurality of transverse passes in traveling through said top bank.

9. A water tube boiler provided with a main bank composed of horizontally-inclined water tubes and angularly-disposed header structures combined in such a way as to form a gas passageway of gradually diminishing cross-sectional area from its lower towards its upper end, a top bank composed of tubes of greater length than most of the tubes of said main bank, a gas uptake leading from one end of said top bank, and a shield arranged above the portion of the top bank that is in proximity to said main bank and provided at its ends with openings that permit some of the gases escaping from the main bank to flow transversely of the tubes of the top bank in traveling to said uptake.

10. A water tube boiler provided with a main bank composed of horizontally-inclined water tubes and angularly-disposed header structures combined in such a way as to form a gas passageway of gradually diminishing cross-sectional area from its lower towards its upper end, a top bank composed of tubes of greater length than most of the tubes of said main bank, a gas uptake leading from one end of said top bank, a shield arranged above the portion of the top bank that is in proximity to said main bank and provided at its ends with openings that permit some of the gases escaping from the main bank to flow transversely of the tubes of the top bank in traveling to said uptake, and a radiant heat bank arranged between said main bank and the combustion chamber.

11. A water tube boiler, comprising a main tube bank composed of tubes of gradually

ally diminishing length from the lower towards the upper end of the bank, angularly-disposed header structures arranged at the opposite ends of said tubes, a top bank composed of relatively long tubes, a radiant heat bank arranged between the combustion chamber and said main bank and composed of tubes of greater length than those con-

stituting the main bank, and means interposed between said radiant heat bank and the lower end portion of one of the header structures of the main bank for protecting the lower portion of said header structure from the fire gases. 10

ALFRED COTTON.
